(57) **CLAIM**

We claim the ornamental design for a broadhead, as shown and described.

DESCRIPTION

FIG. 1 is a side perspective view of a broadhead, showing our new design;

FIG. 2 is a side elevation view thereof;

FIG. 3 is another side elevation view thereof with a rotational offset of approximately 60 degrees from that of FIG. 2;

FIG. 4 is a right side elevation view thereof with a rotational offset of approximately 30 degrees from that of FIG. 2;

FIG. 5 is a left side elevation view thereof with a rotational offset of approximately 90 degrees from that of FIG. 2;

FIG. 6 is a top plan view thereof; and,

FIG. 7 is a bottom plan view thereof.

The broken lines shown represent unclaimed subject matter

and form no part of the claimed design.

1 Claim, 6 Drawing Sheets
